DECORATIVE DISPLAY FORM

Alvin G. Anderson, Framingham, Mass., assignor
to Dennison Manufacturing Company, Fram-
ingham, Mass., a corporation of Massachusetts

Application December 30, 1937, Serial No. 182,543

2 Claims. (Cl. 40—126)

For store window advertising and other purposes it is customary to employ display forms of various sizes and shapes and to change the forms at frequent intervals. Heretofore the usual practice has been to construct such forms of wood or other expensive material and to discard them after short usage.

Objects of the present invention are to produce decorative forms for advertising and other purposes which are attractive in appearance and inexpensive in construction, which are light in weight, which can be shipped and stored in compact form, which are adaptable to a wide variety of shapes, which can be used repeatedly in different shapes and arrangements, and which are generally superior to display forms heretofore known.

In one aspect this invention involves a form comprising a sheet of corrugated material, such as ordinary pulp board, with a facing sheet of cardboard or the like cemented to the crests of the corrugations on one side of the corrugated sheet and preferably on each side. To make the form bendable to the desired shape I provide a series of slits or cuts which extend transversely of the corrugations from one side of the form substantially to the inside of the facing sheet on the opposite side of the form, with the portions of the corrugated sheet between the oblique cuts remaining fast to the uncut facing sheet. Thus the form may be used flatwise, in which case the cuts are visible merely as thin lines on one side of the form, or it may be bent transversely of the corrugations to the desired shape, the cuts preferably being close enough together to afford any one of a wide variety of shapes. The cuts or slits are preferably oblique to the faces of the form and they preferably all incline in the same direction. Either or both of the facing sheets may be painted or otherwise decorated.

In another aspect the invention involves the method of making a display form which comprises cementing a facing sheet to the crests of the corrugations on one or each side of a corrugated sheet, forming in the form a series of closely spaced oblique slits which extend transversely of the corrugations from one side of the form substantially to the inside of the facing sheet on the other side of the form and then bending the form transversely of the corrugations to the desired shape.

For the purpose of illustration a typical embodiment of the invention is shown in the accompanying drawing in which,

Fig. 1 is a plan view of a flat form;

Fig. 2 is a section on line 2—2 of Fig. 1;
Fig. 3 is a section on line 3—3 of Fig. 1; and
Fig. 4 is a cross section of the form bent into the shape of a reversed curve.

The particular embodiment of the invention chosen for the purpose of illustration comprises a corrugated sheet 1 having facing sheets 2 and 3 cemented to the crests of the corrugations on opposite sides of the corrugated sheet. The corrugated sheet 1 and the facing sheet 2 have oblique slits 4 extending therethrough substantially to the inside of the facing sheet 3, terminating at 5.

While the dimensions may of course be varied, depending upon the use to which the forms are to be put and the composition of the sheets, when using paper sheets for window display forms I have found the following dimensions to be highly satisfactory.

	Inch	20
Thickness of uncut facing sheet, including outside decorative coating	.032	
Thickness of cut facing sheet	.030	
Thickness of corrugated sheet	.015	
Space between facing sheets	.165	25
Total thickness of form	.227	
Distance between crests of corrugations	.350	
Distance between cuts	.500	

By virtue of the oblique slits 4 the form may be bent transversely of the corrugations in either direction, although the resistance to bending is greater when the sheet is bent to make the slit side concave. When the sheet is bent to make the uncut side concave the slits open somewhat as shown at the ends of Fig. 4. The bending of the sheet in the direction to make the slit side concave is facilitated by the slits partly because the abutting edges of the cut sheets at the slits slide over each other to a slight extent and partly because these edges are compacted by the compressive force. Thus the sheet can be bent in either direction into a smooth continuous curve without the usual tendency to break at one or more locations along the curve.

It should be understood that the present disclosure is for the purpose of illustration only and that this invention includes all modifications and equivalents which fall within the scope of the appended claims.

I claim:

1. A paper sheet adapted for use in making decorative display forms comprising a sheet of corrugated material and a facing sheet fast to one side thereof, the corrugated sheet having a series

50

55

of juxtaposed oblique slits extending transversely of the corrugations substantially to the inside of the facing sheet and all of the slits inclining in the same direction relatively to the faces of the sheets, said facing sheet being continuous and uninterrupted.

5. A paper sheet adapted for use in making decorative display forms comprising a sheet of corrugated material and a facing sheet fast to

each side thereof, one facing sheet and the corrugated sheet having a series of juxtaposed oblique slits extending transversely of the corrugations substantially to the inside of the other facing sheet, the other facing sheet being continuous and uninterrupted, and all of the slits inclining in the same direction relatively to the faces of the sheets.

5
ALVIN G. ANDERSON.
